DESIGN FOR A BOTTLE

Garland D. Runnels, Seattle, Wash.

Application May 1, 1937, Serial No. 69,104

Term of patent 14 years

To whom it may concern:

Be it known that I, Garland D. Runnels, a citizen of the United States, residing at Seattle, in the county of King and State of Washington, have invented a new, original, and ornamental Design for Bottles, of which the following is a specification, reference being had to the accompanying drawing, forming part thereof.

The configuration of the bottle is uniform throughout its entire circumference with the exception of one smooth spot shown in Figure 1 which is intended to receive a label.

I claim:

The ornamental design for a bottle, substantially as shown and described.

GARLAND D. RUNNELS.
